United States Patent Office

Des. 174,684

Patented May 10, 1955

174,684

APPLIQUE OR SIMILAR ARTICLE

Marjorie J. Elmore, Jefferson City, Mo., assignor to Committee On Public & Patient Education On Professions, Jefferson City, Mo., a nonprofit corporation of Missouri

Application March 29, 1954, Serial No. 29,744

Term of patent 14 years

(Cl. D3—9)

To all whom it may concern:

Be it known that I, Marjorie J. Elmore, a citizen of the United States and a resident of Jefferson City, Missouri, have invented a new, original, and ornamental Design for an Applique or Similar Article, of which the following is a specification, reference being had to the accompanying drawing, forming a part hereof.

The single figure is a face view of an applique or similar article, showing my new design.

The dominant features of my design reside in those portions shown in full lines.

I claim:

The ornamental design for an applique or similar article, substantially as shown and described.
